DESIGN FOR A FLASHLIGHT HEAD

Cyril P. Deibel, Lakewood, Ohio

Application October 22, 1940, Serial No. 95,987

Term of patent 7 years

To all whom it may concern:

Be it known that I, Cyril P. Deibel, a citizen of the United States, residing at Lakewood, in the county of Cuyahoga and State of Ohio, have invented a new, original, and ornamental Design for a Flashlight Head of which the following is a specification, reference being had to the accompanying drawing, forming part thereof, wherein Fig. 1 is a top plan view of the flashlight head showing my new design with the lens removed; Fig. 2 is a side elevational view of the flashlight head with the lens positioned thereon and shown in dotted lines; and Fig. 3 is a horizontal sectional view on the line 3—3 of Fig. 2.

The dominant features of my design reside in the portions shown in full lines.

I claim:

The ornamental design for a flashlight head, as shown and described.

CYRIL P. DEIBEL,
